CAN CLOSURE

Herbert Goldschmidt, 45 Amherst Place, Livingston, N.J.
Filed July 22, 1959, Ser. No. 828,904
3 Claims. (Cl. 220—40)

My invention relates generally to can closures and specifically to can closures which incorporate a tamper-proof seal, sealing means, and a seal breaker.

It is among the objects of my invention to provide a can closure which seals a can until a portion thereof is broken off to enable the closure to be opened.

It is a further object of my invention to provide a can closure which may be unsealed and resealed.

Yet a further object of my invention is to provide a can closure with unseating means.

These objects and advantages as well as other objects and advantages may be achieved by the device illustrated in the drawings in which:

FIGURE 1 is a top plan view of a can having engaging means to receive my can closure;

FIGURE 2 is a side elevational view of a can to which my can closure has been applied;

FIGURE 3 is a view in perspective showing my can closure disengaged from the can;

FIGURE 4 is a view showing a portion of the locking arm; and

FIGURE 5 is a view in perspective showing the can closure positioned on the top of a can.

Referring now to the drawings in detail which show an embodiment of my invention, there is illustrated a pair of diametrical arms 11, 12 of unitary construction joined together at the center by a circular portion 13. The arms 11, 12 are not arranged planar with the circular portion 13 but are joined thereto by bent portions 14, 15. The ends of the arms 11, 12 are provided with upturned portions 16, 17 which define stops. These stops 16, 17 are disposed on opposite longitudinal edges of the arms 11, 12. Opposite the stops 16, 17 and integral with the arms 11, 12 there are formed enlargements 18, 19. These enlargements are deformed downwardly from the plane of the arms 11, 12 and constitute cam surfaces to engage a latch which exerts pressure on the arms to firmly lock the closure in place. One of the enlargements 18 is provided with an upstanding portion 20. This upstanding portion 20 is a detent which prevents the closure from being easily opened. The upstanding portion 20 or detent is provided with a shear line 21. The arms 11 and 12 are formed of relatively resilient metal. The detent 20 when deformed with respect to the cam surface 18 will readily shear off along the line 21. A readily deformable plug 22 is applied to the underside of the circular portion 13. A handle 23 passes through the circular portion 13 and the plug 22 and terminates in a brush or applicator 24.

A can 25 is the container for material which is to be closed and sealed. The can is provided with a top-plate 26. The top of the plate 26 has a central opening 27. Secured to the top 26 in some suitable manner, by welding or by solder, etc. a strap 28 is applied. This strap is formed with an annular central enlargement 29. The enlargement 29 has a central aperture 30. The peripheral edge of the enlargement 29 is provided with a pair of arcuate, generally vertically perpendicular cam surfaces 31, 32. These surfaces at the top, are positioned to engage the under portion of the arms 11 and 12 and raise the plug 22 from engagement with the aperture 27. Thus, when the plug 22 becomes engaged with the aperture 27 by reason of dried material such as glue, the arms 11, 12 ride up the cam surfaces 31, 32 and serve to break the seal of the plug 22 by reason of its engagement with glue disposed about the edges of the opening 27. Thus,

2

the cam surfaces 31, 32 serve to unseat the plug 22 and break the seal. The outer ends of the strap 28 are provided with an upstanding portion 33, 34 disposed generally vertically, and a bent-over portion 35, 36 generally horizontal and parallel with the main portion of the strap 28. Each of the horizontal portions 35, 36 are provided with upturned cam surfaces 37, 38 which are designed to engage with the cam surfaces 18, 19 in order to firmly seat the plug 22 in the opening 27.

When the can 25 is filled through the opening 27 with material to be dispensed by the brush 24, the closure 39 is applied to the opening 27 and the arm 11 is deformed so that the detent 20 will slip under the horizontal portion 36 and the arm 12 will slip under the horizontal portion 35. In this position, as shown in FIGURE 5, the closure 39 seals the opening 27 against discharge of the contents of the can 25. Without the application of extreme pressure, the closure 39 cannot be removed from the can 25 by reason of the abutment of the detent 20 with the horizontal surface 36. It will be seen that these horizontal surfaces 35, 36 define latches to hold the arms 11, 12 so that the plug 22 is locked in place. When it is desired to open the closure, the detent 20 is broken off on the shear line 21 and the arms 11, 12 may then be easily rotated so that the closure 39 may be lifted from the aperture 27. Sealing is subsequently effected by engagement of the cam surfaces 18, 19 with the overlying cam surfaces 37, 38 thereby forcing the ends of the arms 11, 12 under the latches 35, 36. Solidified material collected around the plug 22 is broken as a seal by the action of the cam surfaces 31, 32 on the arms 11, 12 as they are rotated.

The foregoing description is merely intended to illustrate an embodiment of the invention. The component parts have been shown and described. They each may have substitutes which may perform a substantially similar function. Such substitutes may be known as proper substitutes for the said components and may have actually been known or invented before the present invention; these substitutes are contemplated as being within the scope of the appended claims, although they are not specifically catalogued herein.

I claim:

1. A can closure comprising a plug, a pair of resilient radial arms on the plug, a can having an orifice, a pair of arcuate cam-surfaces on the can adjacent to the orifice and engageable with the arms on rotation, a pair of latches attached to the top of the can and positioned to engage the ends of the arms, an upturned cam-surface on each of the latches, a generally horizontal surface on each of the latches, a corresponding downturned cam-surface on the end of each of the arms engageable with the cam-surfaces on the latches and adapted to resiliently deform the arms downwardly to frictionally and resiliently engage the said horizontal surfaces, an up-turned portion on opposite side-edges of each of the arms, the up-turned portions engageable with the latches to limit the progressive engagement of the arms with the latches, a detent on a side-edge of one of the arms opposite to the up-turned portion, a shear-line at the bottom of the detent.

2. A can closure comprising
a readily deformable plug,
a pair of resilient radial arms on the plug,
a first portion on the arms adjacent to the plug extending upwardly and radially,
a second portion on the arms adjacent to the first portion extending horizontally and radially,
a can having an orifice,

a pair of arcuate cam-surfaces on the can adjacent to the orifice and engageable with the arms on rotation,

a pair of latches attached to the top of the can and positioned to engage the ends of the arms,
 an upturned cam-surface on each of the latches,
 a generally horizontal surface on each of the latches,
 a corresponding downturned cam-surface on the end 5 of each of the arms engageable with the cam-surface on the latches and adapted to resiliently deform the arms downwardly to frictionally and resiliently engage the said horizontal surfaces,
 an upturned portion on opposite side-edges of each 10 of the arms, the upturned portions engageable with the latches to limit the progressive engagement of the arms with the latches,
 a detent on a side-edge of one of the arms opposite the upturned portion, and
 a shear-line at the bottom of the detent.
 3. A can closure comprising
 a readily deformable plug,
 a pair of resilient, radial arms on the plug,
 a first portion on the arms adjacent to the plug extending upwardly and radially, 20
 a second portion on the arms adjacent to the first portion extending horizontally and radially,
 a can having an orifice,
 a strap secured to the can diametrical to the orifice 25 in the can,
 an annular enlargement on the strap intermediate its ends having an opening generally coaxial with the orifice in the can,
 a pair of arcuate, upstanding, cam-surfaces formed 30

on the annular enlargement, and engageable with the arms upon rotation,
 a pair of latches formed on the ends of the strap,
 an upturned cam-surface on each of the latches,
 a generally horizontal surface on each of the latches, 5 the ends of the arms normally extending above the horizontal surfaces on the latches,
 a downturned cam-surface on the end of each of the arms normally extending below the upturned cam-surface on each of the latches and engageable therewith upon rotation of the arms to resiliently deform the arms downwardly to frictionally and resiliently engage the said horizontal surfaces,
 an upturned portion on opposite side edges of each of the arms, the upturned portions engageable with the latches to limit progressive engagement of the arms with the latches,
 a detent on a side-edge of one of the arms opposite the upturned portion, and
 a shear-line at the bottom of the detent.
